UNITED STATES PATENT OFFICE.

ERNEST NORMAN KERR, OF ROCK ISLAND, ILLINOIS.

EXPOSURE ATTACHMENT FOR PHOTOGRAPHIC-PRINTING MACHINES.

952,334.

Specification of Letters Patent. Patented Mar. 15, 1910.

Application filed November 23, 1908. Serial No. 463,953.

To all whom it may concern:

Be it known that I, ERNEST N. KERR, a citizen of the United States, and a resident of Rock Island, in the county of Rock Island and State of Illinois, have invented a new and Improved Exposure Attachment for Photographic-Printing Machines, of which the following is a full, clear, and exact description.

10 My invention relates to photographic printing machines, my more particular purpose being to enable the operator to adjust the time of exposure, incidental to the photographic printing, with a high degree of 15 accuracy.

My invention further relates to mechanism for enabling the machine to automatically cut off the light and thus end the exposure of the paper or other article being 20 printed.

25 My invention relates still further to various details for improving generally the efficiency of printing machines used in photography and the like.

Reference is to be had to the accompanying drawings forming a part of this specification, in which similar characters of reference indicate corresponding parts in all the figures.

30 Figure 1 is a fragmentary front elevation of the complete machine, the parts occupying their normal position and the two-part door being closed upon the paper to be held in place and printed; Fig. 2 is a vertical section upon the line 2—2 of Fig. 1, looking in the direction of the arrow, and showing various details of the door and shutter mechanism; Fig. 3 is a fragmentary elevation partly broken away, and showing 35 the shutter which is moved automatically for the purpose of exposing the film and of ending the exposure, the view further showing a train of gearing used in connection with a revoluble fan for timing the exposure; Fig. 4 is a fragmentary section 40 upon the line 4—4 of Fig. 3, looking in the direction of the arrow and showing certain parts closely associated with the release of the shutter for the purpose of allowing it to be raised in order to make the exposure;

45 Fig. 5 is a side elevation, showing the machine as it appears with the two-part door in its uppermost position, the machine being now ready to receive the sensitive paper to be printed; Figs. 6, 7 and 8 are diagrams 50 otherwise similar to Fig. 5, and show the

parts as they appear with the two-part door moved successively into different positions; and Fig. 9 is an enlarged detail, showing in section a bolt slidably mounted upon a portion of the two-part door for the purpose of 60 engaging a roller and thus enabling the latter to control the partial turning of a shaft at intervals.

A casing 10 having generally the form of 65 a box, is provided with an opening 11 to facilitate the entrance of light thereinto. Mounted within the casing 10 and inclined obliquely is a reflector 12 supported upon a board 13. The casing 10 is provided with a 70 drawer 14 for the purpose of storing a quantity of sensitive papers. A rack 16, inclined slightly in relation to the casing, is provided with slots 17 for the purpose of supporting a number of revoluble fans 18, 19, when not 75 in use. These fans are separately used for the purpose of retarding, by their rotation, the time of exposure, the principle being that the larger the fan the more slowly it is 80 adapted to revolve and consequently the longer will be the exposure on a given application of power to the propulsion of the fan. The casing 10 is provided with a vertical 85 partition 20. The fans 18, 19, when mounted in position, appear as indicated at 18^a in Figs. 1 and 3. Each fan is mounted upon a 90 pintle 21, the same being supported at one of its ends by a revoluble shaft 22 and engaged by a dog 23 carried by this shaft.

Mounted within a sub-frame 24 of metal 90 is a train of gearing 25 in which the revoluble shaft 22 is included. A larger shaft 26 is mounted in the top of the sub-frame 24 and extending directly through this shaft is an arm 27, a portion of which projects outside of the casing. The arm 27 carries a button 29 and connected to the latter is a tensile spring 30. The lower end of this spring engages a fastening 31 which is secured directly to the casing. Loosely 100 mounted upon the shaft 26 is a ratchet wheel 32 and engaging the latter is a pawl 33, this pawl being pressed upon by a spring 34. This pawl and spring are adapted to enable the rotation of the shaft 26 to transmit power through the train of gearing 25 to the revoluble fans. The shaft 26 is provided with a reduced portion 35 carrying a dog 36. Disposed immediately adjacent to the dog 36 is a substantially L-shaped arm 110 37 provided with an end 38 (see Fig. 4) which is adapted to engage a leaf spring 39,

this leaf spring being provided for the purpose with a hole 40 into which the end 38 neatly fits. The leaf spring is mounted in a slot 40^a and may be pressed slightly inward—that is, to the right according to Fig. 4—by the action of the dog 36.

Mounted upon the casing 10 are bearings 41, 42 (see Fig. 3) and supported by these bearings is a rocking shaft 43. Encircling 10 this shaft is a sleeve 44 adapted to turn partially. Mounted upon one end of the shaft 43 is a collar 45, and the L-shaped arm 37 above mentioned extends diametrically through the collar 45 and the adjacent end 15 of the shaft 43. A spiral spring 46 is secured directly to the shaft 43 and is wound partially around the same, being connected with a shutter 47 having a rim 47^a whereby it is strengthened. Another spiral spring 20 46^a is connected with the shaft 43 and is also secured by a fastening 46^b to the casing 10. The shutter 47 is provided with an opening 48. A latch 49 (see Fig. 2) is supported upon a rod 50 and is so disposed that when 25 the shutter 47 swings downwardly the opening 48 will be brought substantially into registry with the position of the latch 49, thereby allowing this latch to catch upon the rim 47^a so as to secure the shutter. A leaf 30 spring 51 is mounted upon the rod 50 and tends to hold the latch 49 in proper position for this purpose.

An open frame 52 of substantially rectangular form, is secured upon the casing and is 35 provided with a slot 52^a through which the rod 50 extends. A dog 53 having substantially the form of a thumb piece is connected rigidly with the rod 50, and when under pressure of the thumb may be used for 40 slightly tilting this rod so as to release the shutter 47. The dog 53 is provided with a beveled face 54. A spring 55 engages the point 56 of the framework and also engages the dog 53.

45 Removably mounted within the frame 52 is another frame 57 having substantially a rectangular form and provided with an opening 58. The frame 57 is removable so that any desired number of such frames 50 may be used interchangeably, each having a different size opening 58 to fit the negative. This arrangement does away with a supporting glass for a negative smaller than 55 the opening. This arrangement also excludes the entrance of dust which might otherwise cause extra work afterward. A glass plate 59 rests within the frame 57 which is of proper form to receive it, as will be understood from Fig. 2.

60 Mounted upon the frame 52 are bearings 60 which support a shaft 61. This shaft is encircled by spiral springs 62, 63 which are connected together by a collar 64. The spiral springs 62, 63 are connected with flat 65 bars 65 each beveled at its outer or free end,

as will be understood from Fig. 1. Another flat bar 66 is fastened to the bars 65, and extends toward the arm 27. The bars 65 are further connected together by a flat bar 66^a.

At 67 is a plate provided with a cushion 68 of cloth, or similar material, for the purpose of engaging the paper to be printed. A leaf spring 69 is mounted upon the bar 66^a and is provided with a portion 70 bent slightly outward for the purpose of engaging the beveled face 54 of the dog 53. The plate 67 is mounted upon a bar 71 having substantially an L shape in cross section, this bar being bent upwardly at its ends and journaled upon pivot pins 72 carried by the bars 65. A plate 73 is pivotally mounted upon two links 74 so as to have a slight rocking play relatively to these links which are journaled directly upon the shaft 61. The plates 67, 73 together constitute a two-part door which is held in position by pressure of the bars 65 and parts immediately associated therewith, the plates 67, 73 being, to some extent, independent of each other, however, as will be understood from Fig. 5. 90 When the plates 67, 73 are closed down, as indicated in Figs. 1 and 3, they have the effect of a continuous pad.

Slidably mounted within one end of the bar 66 (see right of Fig. 1) is a sliding bolt 95 75, and engaging this bolt is a leaf spring 76. The bolt 75 has generally the form indicated in Fig. 9 and rests in a slot 66^b adapted to receive it. The bolt 75 is provided with a beveled face 66^c and also with 100 a limiting stop 66^d. This bolt is adapted to press inwardly (that is, downwardly according to Figs. 5 and 9) whenever the beveled face 66^c is moved to the right according to these views, so as to engage and pass underneath a roller 83 carried by the arm 27.

Mounted rigidly upon the bar 66 is an arm 77 and carried by the latter is a button 78 having a beveled face 78^a, this button and a pawl 79 being mounted rigidly upon opposite ends of a pin 80 which is journaled in the arm 77 and free to turn relatively to the same. A plate 81, secured in position by screws 82 (see Fig. 1), holds the sliding bolt 75 in position, thus keeping it in alignment with the general position of the button 78. Mounted within a slot 83^a (see Fig. 1) is a stationary pin 84 which is sometimes engaged by the pawl 79, and when this occurs the pin 84, to some extent, controls 110 115 120 125 130 motions of the button 78.

For convenience I designate the bars 65, 66, 66^a as a "door holder," its purpose being normally to hold the two-part door temporarily closed. When all parts of the machine are in normal position—that is, when the machine is idle—the two-part door is closed and is held closed by the door holder, the shutter 47 being also closed and held by the latch 49.

The casing above the frame 52 is provided with a glazed opening 18^b and above the mirror 12 with a glazed opening 19^a.

The operation of my device is as follows:

5 Supposing the parts to be in their normal positions, the operator places his thumb upon the dog 53, pulling the latter downward slightly, thus releasing the leaf spring 69 and liberating the door holder. He next 10 raises the door holder to the position indicated in Fig. 5, this being the extreme position. In doing this, the operator raises the plate 67 into its extreme position at the top, and owing to the tension of the springs 62, 15 63 (see Fig. 1) the plate 73 (Fig. 5) is raised at practically the same instant as the plate 67, but is separated from the latter by an angle of perhaps thirty-five degrees. The upward movement of the door holder causes 20 the beveled face 66^c of the bolt 75 to engage the under side of the roller 83, the bolt 75 being free to move downwardly a little owing to the resilience of the leaf spring 76 25 engaging it (see Fig. 1) readily passes the roller 83, although the arm 27 occupies the limit of its travel in one direction and is stationary. The button 78 now occupies the position indicated in Fig. 5. The operator 30 opens the drawer 14 and takes therefrom a piece of stock 15 which he places against the glass plate 59. He next grasps the plate 67 and swings the door holder downwardly so as to close the door. In doing this, the bolt 75 engages the roller 83 and, being now 35 unable to pass underneath the roller because the beveled face 66^b slants in the wrong direction for this purpose, the arm 27 is turned, the roller 83 simply rolling against the edge of the bolt 75 and the adjacent edge of the 40 plate 81, which is flush with the same. As the door holder descends farther (see Fig. 6) the button 78, under pressure of the roller 83, as the roller moves from between it and the plate 81, turns into such position that the beveled face 78^a lodges directly against the plate 81, this taking place when the parts 45 occupy the positions indicated in Fig. 6. That is to say, as the roller 83 moves from between the button 78 and the plate 81, the button 78 is pulled against the plate 81 by the spring 78^b; and as the roller 83 returns, it must pass upon the button 78. The downward movement of the door holder being 50 continued still farther, so that the door holder reaches almost its extreme lowermost position, as indicated in Fig. 7, the pawl 79 engages the stationary pin 84 (compare Figs. 1 and 7) and when the movement of the door holder is finally completed, as indicated 55 in Fig. 8, the pawl 79, having passed completely by the pin 84, is now free to turn and consequently the button 78, under tension of the spring associated with it, turns slightly in a clockwise direction, as indicated 60 in Fig. 8, thereby releasing the arm 27

and allowing the latter to return to its normal position. The release of the arm 27 takes place at practically the same instant that the leaf spring 69 clicks into engagement with the dog 53. The rocking movement of the arm 27 in causing the roller 83 to descend turns the dog 36 (see Fig. 3) and thus causes the L-shaped arm 37 to be raised, as will be understood from Figs. 2 and 3, this movement being preparatory to enabling the arm 37 to serve as a limiting stop for the shutter 47 which, however, does not move at this instant. This rocking movement of the arm 27, in thus turning the dog 36 and raising the arm 37, causes the end 38 (see Fig. 4) to first bend the leaf spring 39 slightly back and then pass into the hole 40. The dog 36 having already moved away from the leaf spring 39, the firm engagement of the end 38 with this leaf spring prevents the collar 45 from turning, and consequently prevents the arm 37 from being restored immediately at its normal position. The arm 37 being thus out of the way of the shutter 47 (see Fig. 3), and this shutter being under tension of the spring 46, is ready to fly up as soon as released at its bottom from the latch 49. When, therefore, the door holder (see Fig. 2) is in its lowermost position, so that the end 70 of the leaf spring 69 actuates the dog 53, the rod 50 is tilted slightly, and the latch 49 thereupon liberates the shutter 47 which flies up into the position indicated in Fig. 2. The light is thus admitted through the apertures 11 and 58, the printing paper 100 resting upon the glass 59 (which may be a negative or analogous member), and its exposure is thus commenced. The leaf spring 51 allows the latch 47^a to pass the latch 49 in closing.

Referring now to Figs. 2, 3 and 4, it will be noted that the particular rocking movement of the arm 27 incidental to the descent of the roller 83 in tensioning the spring 30 in effect winds the motor shown at the left 110 of Fig. 3, and that as soon as the roller 83 at the bottom of its stroke is released the spring 30 begins to contract and that the motor gradually runs down as the roller 83 rises to its normal position. The release of 115 this roller is effected as will be understood from Figs. 7, 8, at practically the same instant that the spring 69 engages the dog 53, as shown more particularly in Fig. 8. At this instant the dog 79 carried by the door 120 holder, having engaged and passed by the stationary pin 84, is free to turn, and consequently the button 78 is likewise free to turn, and therefore as soon as the dog 79 is released the arm 27, by turning the button 78 is set free, as indicated in Fig. 8. The arm 27, in being restored to its normal position, moves slowly, for the reason that it can travel no faster than is commensurate with the action of the train of gearing 25 and the 125

speed of this gearing is controlled by the revoluble fans. These fans being of different sizes, as above explained, the time required for the gearing to run down may be apportioned at will. The gearing having run down the dog 36 returns to the position indicated at Fig. 4, and presses the leaf spring 39 inward so as to disengage the end 38. This action disengages the arm 37 from restraint and allows the tension of the spring 46^a (see Fig. 3) to assert itself. This causes the shutter 47 to close with a snap, and as the latch 49 is already in position the light is completely shut off and the shutter 47 held tightly in its closed or normal position.

The action of the machine may be summarized by saying that the operator places in the machine a negative, or another appropriate glass plate, places upon this a sheet of sensitive paper, or other stock to be printed, next lowers the door holder, which carries ahead of it the two-part door and closes the same, and next forces the leaf spring 69 against the dog 53, this action causing the shutter 47 to be released and also controlling the gearing so as to start the same into action. The gearing now runs for a little time, depending upon the size of the fan previously selected, after which the shutter 47 closes with a snap.

Having thus described my invention, I claim as new and desire to secure by Letters Patent:

1. The combination of a revoluble shaft, a shutter loose relatively thereto and adapted to be opened and closed, an arm connected with said shaft and provided with a portion for engaging said shutter, a spring connected with said shaft for turning the latter so as to cause said arm to close said shutter, means for temporarily restraining said arm so as to leave said shutter open, and time-controlled mechanism for releasing said arm.

2. The combination of a revoluble shaft, a shutter mounted loosely upon said revoluble shaft as a center, an arm connected with said revoluble shaft and adapted to close said shutter when said shaft is turned, means for turning said shaft, mechanism for temporarily locking said shaft so as to prevent the same from turning, a second revoluble shaft, and means controllable by said second revoluble shaft for releasing said first-mentioned shaft.

3. The combination of a revoluble shaft, a shutter mounted loosely upon said revoluble shaft as a center, an arm connected with said revoluble shaft and adapted to close said shutter when said shaft is turned,

means for turning said shaft, mechanism for temporarily locking said shaft so as to prevent the same from turning, a second revoluble shaft, a dog mounted thereupon, and mechanism controllable by movements of said dog for releasing said first-mentioned shaft. 65

4. The combination of a revoluble shaft, a shutter mounted loosely upon said revoluble shaft as a center, an arm connected with said revoluble shaft and adapted to close said shutter when said shaft is turned, means for turning said shaft, mechanism for temporarily locking said shaft so as to prevent the same from turning, a second revoluble shaft, and mechanism controllable by 75 said second-mentioned shaft for releasing said first-mentioned shaft.

5. The combination of a shutter adapted to be opened and closed, means including a revoluble member for closing said shutter, 80 mechanism for temporarily locking said revoluble member so as to prevent said shutter from closing, and time-controlled mechanism including means for releasing said revoluble member.

6. The combination of a shutter adapted to be opened and closed, means including a revoluble member for closing said shutter, mechanism for temporarily locking said revoluble member so as to prevent said shutter 90 from closing, a second revoluble member, time-controlled means for actuating the same, and a dog mounted upon said second revoluble member for the purpose of releasing said first-mentioned revoluble member. 95

7. The combination of a shutter adapted to be opened and closed, means including a revoluble member for closing said shutter, mechanism for temporarily locking said revoluble member so as to prevent said shutter 100 from closing, time-controlled mechanism including means for releasing said revoluble member, said time-controlled mechanism further including a movable arm for the purpose of starting said time-controlled 105 mechanism into action, mechanism for temporarily restraining said roller so as to prevent said movable arm from starting, and means controllable at will for actuating said mechanism.

In testimony whereof I have signed my name to this specification in the presence of two subscribing witnesses.

ERNEST NORMAN KERR.
